UNITED STATES PATENT OFFICE.

HARRY O. MAMAU, OF PITTSBURGH, PENNSYLVANIA.

PADDED ROLL.

Application filed December 19, 1921. Serial No. 523,476.

To all whom it may concern:

Be it known that I, HARRY O. MAMAU, a citizen of the United States, residing at Pittsburgh, in the county of Allegheny and 5 State of Pennsylvania, have invented new and useful Improvements in Padded Rolls.

My invention relates to padded rolls, and more particularly to padded ironing-machine rolls.

- 10 The usual ironing machine has a heated metal shoe which presses clothes and other fabrics to be ironed against the periphery of a padded rotating roll, having a mandrel on which the padding is wound spirally.
- 15 Attempts have been made to use as padding for ironing rolls what is known as cotton padding having strands or rovings of cotton. These rovings have quite a large diameter, so that the padding containing them 20 may be one-fourth of an inch or more thick. This padding is wound around a central support or mandrel a plurality of turns, but it has been impossible to prevent a ridge or bump extending lengthwise of the roll where 25 the padding ends. Another object is to provide an ironing-machine roll having thereon a padding which does not have such bump or ridge.

Referring to the accompanying drawing, 30 Fig. 1, is an end view of a roll with the padding and cover; Fig. 2, a plan view of a part of a padded roll with the cover omitted; Fig. 3, a plan view of a part of a fringed end of a piece of padding; and 35 Fig. 4, an end view of a fragment showing a modification.

On the drawings 1 designates a mandrel on which the cotton padding 2 has been wound three turns, 3 designating the inner 40 end of the padding and 4 the outer end. The padding comprises the parallel cotton rovings 5 and the groups of cross threads 6 arranged approximately one-fourth of an

inch apart though the distance may be somewhat more or less. 45

To prevent the formation of the ridge, rib or bump referred to herein, I provide one or both ends of the padding with a fringe 8 composed of the rovings which extend beyond the final cross or binding threads 6. This fringe preferably extends beyond the terminal warp or binder threads about an inch or an inch and a half, but it may be somewhat longer or shorter.

In winding the padding on the mandrel 55 the outer end of the padding preferably lies near the radial plane of the inner end. Preferably, the free end of the fringe originally slightly overlies the inner end.

The fringe is very soft and yielding and 60 will distribute itself so as to make a substantially smooth surface over the inner end of the padding.

On Fig. 4, I show the padding with both 65 ends fringed, the outer fringe 8 overlapping or overlying the inner fringe 9. The overlap should be such as will make the roll smooth along the fringe 8 after the creeping of the padding has stopped.

I claim—

1. An ironing machine roll having a mandrel, a covering for the mandrel comprising parallel cotton rovings, and means for connecting them together, their outer ends forming a fringe overlying the inner end 75 of the padding so as to form a joint flush with the periphery of the roll.

2. An ironing machine roll having a mandrel, a covering for the mandrel comprising parallel rovings of cotton bound together and having both ends fringed, the fringe at one end of the rovings overlying 80 the fringe at the other end thereof.

Signed at Pittsburgh, Pa., this 16 day of Dec. 1921.

HARRY O. MAMAU.
